UNITED STATES PATENT OFFICE

ABRAHAM G. FELDMAN, OF CHICAGO, ILLINOIS

INFANT'S COLLAPSIBLE BATHTUB

Application filed September 24, 1928. Serial No. 308,066.

My invention relates to infants' bath tubs of the collapsible type, and more particularly to the structural make-up of such bath tubs for the disposal of the dressing table and accessory-rack features thereof, and my main object is to provide a firm and durable support for the dressing table element.

A further object of the invention is to dispose the dressing table element for easy movement by the use of a novel bearing assembly.

A still further object of the invention is to provide the dressing table element with a stop device to assure the stability of its position during use.

Another object of the invention is to dispose the accessory rack in the structure of the bath tub and independent of the dressing table element, so that the movement of the latter has no effect upon the accessory rack.

A final, but nevertheless important object of the invention is to accomplish the improvements by the use of few and simple parts, in order that the cost of the appliance may not be materially increased.

With the above objects in view, and any others which may suggest themselves from the description and claims to follow, a better understanding may be gained from the accompanying drawings, in which Figure 1 is a perspective view of the article in open form and with the dressing table in position for use;

Figure 2 is an end view of a fragment of the showing in Figure 1;

Figure 3 is an end view of the article in collapsed form;

Figure 4 is an enlarged elevation of a detail; and

Figure 5 is a horizontal section of the said detail, partly in elevation.

In the field of collapsible bath tubs, it is customary to construct the stand or frame of the same as indicated clearly in Figure 1, the legs 10 being crossed at each end of the article with a pivotal connection 11. At the bottom, the legs receive longitudinal braces 12, while at the top the braces are denoted by 13. Ordinarily, the stand is intended to hold but the tub 14 within it, the connection with

the dressing table 15 and the accessory rack 16 being extraneous. Under those conditions, an infirm and wobbly disposal is made for the dressing table, so that the handling of the same requires extra care, and the dressing table does not hold its place well when in position for use; in fact, the dressing table is in danger of collapse while the infant is being dressed and to cause an accident. As to the accessory rack, the support therefor is commonly associated with the dressing table rather than with the stand, so that not only is an insecure position had by the accessory rack, but in the event that the dressing table is dropped to a position of non-use, the accessory rack follows suit and assumes a remote or dropped position. Obviously, the articles in the rack not only assume an inaccessible position at such a time, but they may also readily shift their positions or drop to the floor, to become soiled or lost. I have departed from the undesirable construction of the dressing table and accessory rack elements as designed in the past, and provide improvements in this line which accomplish the objects recited above to their fullest extent.

In taking up the dressing table 15, I do not vary its general design, but provide at the front a depending piece 16^a which is adapted to over-hang the frontal rail 13 of the stand, as clearly shown in Figure 2. This piece receives the usual handle 17 for the dressing table. It will be seen that with the latter in horizontal position, and the piece 16^a immediately in front of the rail 13, it will be impossible to shift or unseat the table whereby to cause the same to recede and drop. The piece or drop 16^a thus locks the table to remain in its frontal position during use, and is therefore safe for the dressing of the infant.

At the rear, the dressing table 15 is supported by pins 18 directed inwardly from the corresponding legs 10 of the stand. Each of the pins has a head 18^a at its inner end, a loose roller 18^b next to the head, and a washer 18^c between the roller and the leg 10. The roller 18^b and the head 18^a are disposed in a groove 15^a made in each end piece 15^b of the

dressing table, the rollers being somewhat larger in diameter than the heads and riding freely in the grooves 15^a as the dressing table is drawn forth to be placed in position for use, or pushed back to be hung from the pins 18 as indicated in Figure 3 in a position of non-use. The mere changes of position undergone by the dressing table are not novel in my construction; however, the fact that the pins are held by the legs 10 of the stand and that their rollers travel in grooves in the ends of the dressing table is representative of novelty; also, the fact that the pins are now roller bearing makes for greater freedom in the movement of the dressing table, so that much less exertion is required to draw the same forth or to slide it back. To keep the pins 18 in firm position, their outer ends are screw-threaded as indicated at 20 19, to receive washers 20 and cap nuts 21, the washers 20 of course serving to prevent the marring of the legs 10 of the stand. It is significant that the dressing table is now directly related to the stand of the article, and 25 cannot depart from the latter. In either position, the dressing table has a definite support and cannot depart of itself or through the influence of vibration during use. In other words, the direct connection of the 30 dressing table to the upper ends of the legs 10 gives it a stable point of support.

Relative to the accessory rack, which is commonly provided with pockets 22 to receive accessory articles such as powder puffs, 35 pin cushions, towels, and the like, it will be noted that the frame 23 of the same is pivoted at the ends in the upper extremities of the legs 10 which carry the pins 18. The accessory rack is thus permanently located in the 40 handy position intended for it, and does not vary its position with that of the dressing table. In fact, the accessory rack is entirely independent of the dressing table, and cannot be swung to a position to release its contents. 45 Only when the stand is collapsed or gathered 50 is it advisable to swing the accessory rack forward to make the structure more compact, the extent of this swing as indicated in Figure 3 being but partial and not sufficient to cause the loss of any articles in the rack.

From the above description, it will be seen that I have improved the conventional infant's collapsible bath tub with features making for greater safety, dependability, ease of handling and accessibility. The features I have added involve few and simple parts, and do not add materially to the cost of manufacturing the article; in fact, the gain in efficiency makes up in far greater measure 55 what excess may be involved in the cost of producing the article.

I claim:

1. A stand for collapsible bath tubs, comprising spaced units of crossed legs, extensions of corresponding legs of the units, an

accessory rack pivotally carried by the extensions, and the latter having shoulders adapted to engage a portion of said rack adjacent the pivot axis to support the same in upwardly inclined position while in use. 70

2. A stand for collapsible bath tubs, comprising spaced units of crossed legs, extensions of corresponding legs of the units, an accessory rack pivotally carried by the extensions, the latter having shoulders adapted 75 to engage a portion of said rack adjacent the pivot axis to support the same in upwardly inclined position while in use, and said rack being swingable upon the upper ends of the legs above the tub when the device is collapsed to serve as a closure and protection for 80 the tub and upper ends of the legs. 85

In testimony whereof I affix my signature.

ABRAHAM G. FELDMAN.
